UNITED STATES PATENT OFFICE.

EMANUEL S. ULLMANN, OF NEW YORK, N. Y.

APPARATUS FOR MOORING DIRIGIBLES AND THE LIKE.

1,349,593.

Specification of Letters Patent. Patented Aug. 17, 1920.

Application filed August 2, 1919. Serial No. 314,830.

To all whom it may concern:

Be it known that I, EMANUEL S. ULLMANN, a citizen of the United States, and a resident of the borough of Manhattan, in the city and State of New York, have invented certain new and useful Improvements in Apparatus for Mooring Dirigibles and the like, of which the following is a specification.

My invention relates to devices and means for mooring or anchoring airships of various types, being more particularly intended for securing the type of airships commonly called dirigible balloons or "dirigibles".

The object of the invention is to provide means whereby such an airship, having arrived at a stopping place, may be easily moored to the ground in an expeditious and secure manner, moved from place to place, as into or out of a hangar, while still moored, and released in order to renew or resume its journey.

The invention consists in the novel construction, arrangement and combination of various devices and parts, as hereinafter defined in the claims.

In the drawings, Figure 1 is a general view showing a side elevation of a dirigible balloon of an ordinary type, and showing in cross section a portion of the means by which the same is moored to the ground; Fig. 2 is a plan view of a portion of said mooring devices, hereinafter more fully described; Fig. 3 is a plan view of said mooring devices; and Figs. 4 and 5 are detail views on an enlarged scale, hereinafter more particularly described.

It is well known that when an ordinary dirigible balloon arrives at a stopping place, particularly if any appreciable degree of wind prevails at the time, considerable difficulty is experienced in mooring the airship to the ground in such a manner as to securely hold the same and at the same time without injury. If the airship is a moderately large one, and if the prevailing wind is strong, and especially if the same is variable as to force or direction, the mooring of the dirigible and the continued holding of the same in a safe position, becomes a very difficult and even dangerous proceeding, requiring the services of a great number of men and the supervision of experienced and skilled directors of the work. It is considered necessary to keep the dirigible pointed up into

the wind, and to allow the rear portion to swing around from side to side as the varying currents of air strike the same, at the same time holding the rear portion down by ropes of considerable length. Unless the lower ends of these securing ropes are swung around corresponding to the swinging motion of the rear portion of the dirigible, the latter would be dashed to the ground and injured, and the only method which has thus far been employed for accomplishing this purpose is to have the lower ends of the various ropes held by a sufficient number of men to hold the dirigible down, who travel around to different parts of the field as the wind swings the dirigible into different positions, in order to maintain the lower or mooring end of the rope approximately underneath the body of the dirigible, and this continual supervision must be continued until the dirigible can be drawn into a suitable hangar, if one be present; if no hangar is in existence, the personal manual management of the dirigible must be continued during the whole time of its stay on the field and until it resumes its journey. My invention seeks to provide a safe and secure mechanical method of mooring the dirigible, which will allow it to swing freely in any direction into which the wind may impel the same.

In carrying my invention into effect in the embodiment thereof which I have selected for the purpose of description in this specification and illustration in the accompanying drawings I provide, in or near the central part of a suitable open space a size proportioned to the length of the dirigibles which are expected to be moored, devices to which may be secured the forward portion of the dirigible, and around said central part I provide a series of concentric channels in which are located devices to which the mooring ropes may be secured which drop from the rearward portions of the dirigible. In connection with the above specified parts I provide a series of radial channels extending from said central part, across said concentric channels and leading respectively into hangars located around the open space mentioned, said radial channels being also adapted to receive the mooring devices above spoken of as being located in said central part and said concentric channels, and to permit said mooring devices to pass there-

along and thereby transfer the dirigible into one of the hangars. The above mentioned devices are shown in general plan in Fig. 3 of the accompanying drawings, the hangars, 5 however, not being shown, the radial channels leading thereto being broken off not far from the outermost concentric channel, the said view showing the dirigible in line with one of the radial channels, with the mooring 10 devices, shown in dotted lines, adjusted so as to permit the same to pass along said radial channel and to convey the dirigible into the hangar which would be located in the direction of the lower right hand corner 15 of the drawing. The details of this construction will now be described.

Referring now to the left hand part of Fig. 1 and also to Fig. 2, which is a plan view of the central station or pit and a 20 pivotal traveling mooring device to which is secured the mooring rope depending from the forward part of the dirigible, it will be seen that a series of supports 11, which may be wedge-shaped posts of concrete or the 25 like securely embedded in the ground, are provided, arranged in a circular line as shown in Fig. 2. To each of these posts is bolted a plate 12 of triangular shape, the apex of which is located near the center of 30 the pit and the curved base of which extends outward as far as the first concentric channel. The series of plates 12 are so arranged that between them are a series of radial slots 13, corresponding to the radial 35 channels above referred to. Located in said central pit and underneath the inner ends of the plates 12 is a truck or trolley, preferably of the construction shown, (see Figs. 4 and 5) having four wheels 14 mounted in 40 pairs upon axles 15 connected together by a reach 16 which is provided with an upwardly extending member 17 having a swivel-eye 18 at the upper end to which may be secured mooring ropes. Referring 45 now more particularly to Figs. 4 and 5 it will be seen that to the under side of the plates 12 are bolted angle irons 19, to which is secured a support or trackway 20 for the truck. The member 17 extends upward 50 through the slot 13.

The concentric channels above referred to are formed in the following manner: Referring now more particularly to Fig. 1 it will be seen that posts of concrete or the 55 like 11, similar to those described in connection with the central pit, are provided, extending around in concentric circles for each of the channels. The outer curved bases of the triangular plates 12 are supported by and secured to such posts, and outside of said curved bases is left a circular slot 21. Beyond this circular slot and extending outward to the next concentric channel, and between the radial channels 13 60 (see Fig. 3) is a series of frames or plates

22, the edges of which are supported by posts similar to those already described, and outside of these, a slot 23 intervening, is another series of frames or plates 24 and outside of these again, a slot 25 intervening, 70 is still another series 26, outside of which, a slot 27 intervening, is a last series 28 forming an outer periphery of the whole series. It will be understood that all of the various plates described are supported upon concrete posts, and that between them are left the circular slots mentioned, as well as the radial slots 13, all of which will be clear by referring to Fig. 3.

On the under side of the various plates 80 mentioned I provide a construction similar to that illustrated in Figs. 4 and 5, and adapted to support a truck or trolley similar to that already described in connection with the central pit. One of these trolleys is 85 shown in Fig. 3, the plates being broken away to clearly exhibit the same, and a series of the same is shown in Fig. 1. Each of these trolleys is adapted to secure the lower end of a mooring rope depending 90 from the dirigible as shown in Fig. 1. If desired, more than one rope may be secured to each trolley.

At each intersection of a circular slot with a radial slot, the trackway for the 95 trolley is of a construction which will permit of the turning of the trolley as shown in Fig. 3, in order that the trolleys running around in the concentric channels may at such points of junction be turned so that 100 they may run in a radial slot when it is desirable to move the dirigible from the mooring field into hangars. For this purpose the trackways are flared at the intersections or otherwise constructed so as to 105 permit such turning of the trolleys.

The radial and concentric channels may be constructed in any suitable form of runway which will afford the mooring devices underneath engagements therewith, where- 110 by the mooring devices are held against upward movement while traveling along the runways.

It will be obvious that my invention may be constructed in other forms and embodiments without departing from the spirit 115 and scope of the same. The particular type of truck or trolley which has been described is not essential, any form of movable mooring device might be employed; and also the 120 particular form of channels or runways for the trolleys which I have described is not essential, as it is obvious that any arrangement of such channels or trackways, which would permit a trolley or other movable 125 mooring means to pass around freely therein, would be within the spirit of my invention. It is obvious that the invention is not limited in application to the mooring of airships of the lighter-than-air class, but 130

that it might also be employed for securely mooring to the ground heavier-than-air machines or aeroplanes, which, when resting in positions where no hangars are available, 5 require almost as much as do dirigibles, to be securely moored and yet at the same time be free to swing around in various directions according to the direction of the wind.

The operation of the various devices comprised in my invention will be entirely clear 10 from the drawings in connection with what has been said while describing the construction, and I do not think it necessary to further explain the manner in which the invention is to be employed.

The advantages of my invention have also 15 been alluded to and will be clearly obvious from what has been above said with regard to the construction and operation of the invention.

Having thus described my invention, what I claim as new and desire to secure by Letters Patent is as follows:

1. In an apparatus for mooring dirigibles 20 and the like, the combination with a series of movable mooring devices located below a dirigible and means adapted to connect such dirigible to said mooring devices; of means adapted to secure all of said mooring devices against upward movement, comprising members arranged radially under which all of said mooring devices are adapted to pass radially, and members arranged circularly under which one of such mooring 25 devices is adapted to pass circularly.

2. In an apparatus for mooring dirigibles and the like, the combination with a series of movable mooring devices located below a dirigible and means adapted to connect such dirigible to said mooring devices; of means adapted to secure all of said mooring devices against upward movement, comprising members arranged radially under which all of said mooring devices are adapted to 30 pass radially, and members arranged circularly under which one of such mooring devices is adapted to pass circularly: whereby a dirigible secured near one end to one of said mooring devices centrally located in 35 the apparatus, and secured farther away from said end to another of said devices located away from the center and along the line of said circularly situated members, may be free to swing around circularly or 40 to move radially toward or away from the center of the apparatus.

3. In an apparatus for mooring dirigibles and the like, the combination with a series of movable mooring devices located below a 45 dirigible and means adapted to connect such dirigible to said mooring devices; of means adapted to secure all of said mooring devices against upward movement, comprising members arranged radially under which all 50 of said mooring devices are adapted to pass

radially, and members arranged circularly under which one of such mooring devices is adapted to pass circularly, said members consisting of guides or trackways for said mooring devices, secured to the ground: 70 whereby a dirigible secured near one end to one of said mooring devices centrally located in the apparatus, and secured farther away from said end to another of said devices located away from the center and 75 along the line of said circularly situated members, may be free to swing around circularly or to move radially toward or away from the center of the apparatus.

4. In an apparatus for mooring dirigibles 80 and the like, the combination with a plurality of traveling mooring devices, one of which is adapted to serve as a pivotal mooring device, and means adapted to connect a dirigible to said mooring devices respectively; of means for securing all of said traveling mooring devices against upward movement, while permitting all of said traveling mooring devices except the pivotal 85 traveling mooring device to travel around 90 circularly, and permitting all of said traveling mooring devices, when desired, to travel radially with respect to the circular paths of said mooring devices in a predetermined direction; comprising a series of concentric 95 guides or trackways for certain of said traveling mooring devices, a central station for said pivotal traveling mooring device, and a series of radial guides or trackways extending outward from said central station, said central station being adapted to 100 permit said pivotal traveling mooring device to turn to position to travel in any one of said radial guides or trackways.

5. In an apparatus for mooring dirigibles 105 and the like, the combination with a plurality of traveling mooring devices, one of which is adapted to serve as a pivotal traveling mooring device, and means adapted to connect a dirigible to said mooring devices 110 respectively; of means for securing all of said traveling mooring devices against upward movement, while permitting all of said traveling mooring devices except the pivotal traveling mooring device to move 115 around circularly, and permitting all of said movable mooring devices, when desired, to travel radially with respect to the circular paths of said mooring devices in a predetermined direction; comprising a series 120 of concentric guides or trackways for certain of said traveling mooring devices, a central station for said pivotal traveling mooring device, and a series of radial guides or trackways extending outward from said central station, said central station being adapted to permit said pivotal traveling mooring device to turn to position to travel in any one of said radial guides or trackways, said guides or trackways comprising 125 130

- 4
- a foundation secured to the earth and adapted to control said traveling mooring devices.
6. In an apparatus for mooring dirigibles and the like, the combination with a plurality of traveling mooring devices, one of which is adapted to serve as a pivotal traveling mooring device, and means adapted to connect a dirigible to said mooring devices respectively; of means for securing all of said traveling mooring devices against upward movement, while permitting all of said traveling mooring devices except the pivotal traveling mooring device to travel around circularly, and permitting all of said traveling mooring devices, when desired, to travel radially with respect to the circular paths of said mooring devices in a predetermined direction; comprising a series of concentric guides or trackways for certain of said traveling mooring devices, a central station for said pivotal traveling mooring device, and a series of radial guides or trackways extending outward from said central station, said central station being adapted to permit said pivotal traveling mooring device to turn to position to travel in any one of said radial guides or trackways, said guides or trackways comprising a foundation secured to the earth and means projecting laterally therefrom adapted to control said traveling mooring devices.
7. In an apparatus for mooring dirigibles and the like, the combination with a plurality of traveling mooring devices, one of which is adapted to serve as a pivotal traveling mooring device, and means adapted to connect a dirigible to said mooring devices respectively; of means for securing all of said traveling mooring devices against upward movement, while permitting all of said traveling mooring devices except the pivotal traveling mooring device to travel around circularly, and permitting all of said traveling mooring devices, when desired, to travel radially with respect to the circular paths of said mooring devices in a predetermined direction; comprising a series of concentric guides or trackways for certain of said traveling mooring devices, a central station for said pivotal traveling mooring device, and a series of radial guides or trackways extending outward from said central station, said central station being adapted to permit said pivotal traveling mooring device to turn to position to travel in any one of said radial guides or trackways comprising a foundation secured to the earth, devices extending laterally therefrom adapted to prevent the upward movement of said traveling mooring devices, and devices extending downward and then laterally underneath said traveling mooring devices adapted to support the same.
8. An airship mooring apparatus comprising a circular runway, a radial runway intersecting said circular runway, and traveling mooring devices having underneath engagement with said runways and provided with means for connection with mooring 70 ropes of an airship.
9. An airship mooring apparatus comprising a circular runway, a series of radial runways intersecting said circular runway, and traveling mooring devices having underneath engagements with said runways and provided with means for connection of the mooring ropes of an airship. 75
10. An airship mooring apparatus comprising a series of concentric runways, a series of radial runways intersecting said concentric runways, and traveling mooring devices having underneath engagements with said runways and provided with means for connection of mooring ropes of an airship. 80
11. An airship mooring apparatus comprising a series of concentric runways, a series of radial runways intersecting said circular runways, a mooring device initially 90 located at the central intersection of said runways, adapted to travel along said radial runways with underneath engagements therewith and provided with means for connection with a primary mooring rope at the 95 forward portion of an airship, and a series of mooring devices adapted for connection with successive mooring ropes of the airship and movable in said concentric runways in underneath engagement therewith to conform to the lateral swing of the ship during the mooring operation and movable in either of said radial runways in underneath engagement therewith for disposing said ship in a hangar. 100
12. In an apparatus for mooring dirigibles and the like the combination with a plurality of movable mooring devices located below a dirigible and means adapted to connect such dirigible to said mooring devices; of means adapted to secure said mooring devices against upward movement, comprising a member arranged circularly under which one of such mooring devices is adapted to pass circularly. 110
13. In an apparatus for mooring dirigibles and the like the combination with a plurality of mooring devices located below a dirigible and means adapted to connect such dirigible to said mooring devices; of means adapted to secure said mooring devices against upward movement comprising a member arranged circularly under which one of such mooring devices is adapted to pass circularly: whereby a dirigible secured near one end to one of said mooring devices centrally located in the apparatus and secured farther away from said end to another of said devices located away from the center and along the line of said circularly 115 120 125 130

situated member, may be free to swing around circularly.

14. In an apparatus for mooring dirigibles and the like the combination with a plurality of mooring devices located below a dirigible and means adapted to connect such dirigible to said mooring devices; of means adapted to secure said mooring devices against upward movement comprising

ing a central station for one of said mooring devices and a guide or trackway arranged circularly under which another of such mooring devices is adapted to pass circularly.

Signed at New York city, N. Y., this 31st 15
day of July, 1919.

EMANUEL S. ULLMANN.
